UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed May 16, 1922. Serial No. 561,297.

The present invention relates to devices for attaching typewriting machines to the desks or work tables on which the same are used; and, more particularly, to a typewriter equipment including devices for detachably securing portable typewriting machines to work tables such as drop-leaves of desks or the like.

A feature of the present invention is the provision of a portable typewriting machine-casing having, as one wall thereof, a board or piece to which the base of the machine is held; together with hold-fast means, on a work table, such as a drop-leaf or table-plate form, directly engageable with such base-board or casing-piece (when the casing is open), to hold the baseboard and connected machine.

A further feature of the invention is the provision of a work table-connection, as aforesaid, for a typewriting machine, comprising a casing-piece; which connection may be rendered effective and may be released, upon simple locking or unlocking and movement of the casing-piece upon the table.

A still further feature of the invention is a lock controlled by a finger-piece for holding the casing-piece in position within the hold-fast means on the work table or drop-leaf.

Other features and advantages will hereinafter appear.

In the accompanying drawings,

Figure 1 is a view, in side elevation, showing the machine secured to a work table.

Figure 2 is a view, in front elevation, of the structure shown in Figure 1.

Figure 3 is a plan view of the casing wall to which the typewriter is attached and of the hold-fast devices on the work table, by means of which the machine is held and locked in position.

Figure 4 is a view, in cross-sectional side elevation, showing the manner in which the board, to which the machine is directly secured, forms part of the casing of the machine.

The machine is indicated in dot-and-dash lines by its main frame 10, its keys 11, platen 12 and ribbon-spools 13. The frame 10 is connected to a base 14, forming one wall of the casing therefor. In addition to the base 14, the casing comprises a cover 15. When the cover 15 is positioned over the machine and locked to the base 14, an enclosed cas-

ing is formed, in which the machine may be carried from place to place.

The machine intended to be illustrated in the drawings is the Underwood portable standard typewriting machine, which is secured to the base or casing-piece 14 by means of inturned flanges 16 extending along the sides of the frame 10, connected by a cross-piece 17. In positioning the machine 10 on the casing-piece 14, the flanges 16 are slipped under a pair of clamps 18 on the rear of the casing-piece 14, and thereafter screws 18^a are passed through the flanges 16 and into the casing-piece 14 to hold the machine against displacement on the casing-piece 14; resilient feet or cushions usually being interposed between the flanges 16 and base or casing-piece 14 so that, when the casing-cover 15 is removed, the machine and casing-piece 14 are movable as a unit.

Referring to Figure 2, it will be noted that the casing-piece 14 projects laterally beyond the sides of the frame 10 of the machine, to form, in effect, a flange or ledge extending along the machine-frame at each side thereof; and that the outer rim 27 of the casing-piece 14 extends upwardly an appreciable distance above the upper or inner surface 28 of the casing-piece 14. Extending from front to rear on a table-platform or drop-leaf 19 are hold-fast devices including two elongated angle-irons 20, secured to the work table or drop-leaf by screws 21. These angle-irons 20 are preferably formed from a blank and bent or offset laterally toward each other, at their upper edges, forming lips 22 co-operative with the top surface of the work table to produce channels in which the casing-piece rim 27 may be received, and by means of which the casing-piece 14 may be held down to the drop-leaf or platform. At their rear ends, the angle-pieces 20 having integral offsets or ears 23 directed toward one another, which serve as permanent stops to arrest and hold the casing-piece 14 at its rear, when the casing-piece shall have been received in the channels formed by the angle-pieces.

The lower or outer surface 29 of the casing-piece 14 is provided with outer feet 30, one preferably adjacent to each corner thereof, preferably formed of suitable resilient material such as rubber. These feet 30 rest upon the work table 19.

In the drop-leaf or table, at the front

thereof, is formed a recess 24 adapted to receive a pin or peg 25, having a knurled finger-piece 26, by means of which it may be inserted into, and removed from, the recess 24. 5 After the casing-piece 14 of the machine has been slid into the position, under the offsets 22, and brought to rest by the stops 23, the peg 25 is inserted in the recess 24 and serves as a lock to prevent forward displacement 10 of the casing-piece of the machine. Upon withdrawal of the peg 25, however, the casing-piece may be slid forward to remove the machine from the table.

15 Variations may be resorted to within the scope of the invention, and portions of the improvements may be used without others.

Having thus described my invention, I claim:

1. A typewriter equipment comprising in 20 combination a work table, a base-piece upon which the hood of a portable typewriter is adapted to be mounted, a portable typewriter detachably attached to said base piece and means on the work table to secure 25 the base piece, said means including a holdfast at each of two opposite sides of said work table engageable with respective opposite sides of said base piece, a stop at the rear of said work table engageable with the 30 rear of said base piece, and a forward locking member on said work table engageable with the front of said base piece, all positively holding the typewriter and attached base piece in position on the work table.

35 2. A typewriter equipment comprising in combination a work table, a base piece upon which the hood of a portable typewriter is adapted to be mounted, a portable typewriter detachably attached to said base piece 40 and means on the work table to secure the said base piece thereto, said means including a holdfast at each of two opposite sides of said work table engageable with respect to opposite sides of said base-piece, each of said 45 holdfasts comprising a unitary elongated angular body secured to said work table and having an inwardly projecting upper lip to hold the base piece down onto the work table and an inwardly bent offset rearward portion affording a limiting stop at the 50 rear of said work table engageable with the rear of said base piece and a forward locking pin on said work table engageable with the front of said base piece all posi-

tively holding the typewriter and attached 55 base piece down in position on the work table.

3. A typewriter equipment comprising in combination a work table, a base-piece upon which the hood of a portable typewriter is 60 adapted to be mounted, a portable typewriter detachably attached to said base-piece, and means on the work table to secure the base piece thereon, said means including a holdfast at each of two opposite sides of 65 said work table engageable with respective opposite sides of said base-piece, each of said holdfasts comprising a unitary elongated angular body securable to said work-table, having an inwardly projecting upper lip 70 to hold the casing base-piece onto the work table, and an inwardly bent offset rearward portion affording a limiting stop at the rear of said work table engageable with the rear of said base-piece, and a forward 75 locking member on said work table engageable with the front of said base-piece all positively holding the typewriter and attached base piece down in position on the work table, said forward locking member comprising 80 a stop pin removably insertible in a hole formed in said work table, and said casing and base-piece having a plurality of feet resting on said work table.

4. A typewriter equipment comprising in 85 combination a work table, a base-piece upon which the hood of a portable typewriter is adapted to be mounted, a portable typewriter detachably attached to said base-piece and holdfast means for removably anchoring the base-piece to a work table or the like while the typewriter machine remains attached to the base-piece, including a plurality of elongated unitary angle pieces securable to the work table and under which 90 the edges of the base-piece of the typewriter may be held to prevent the rising of the base-piece and attached machine from the work table and to hold the same against lateral movement, said angle pieces having 95 integral offsets or ears on the ends thereof to locate the position of the base-piece and attached machine upon the table, and means setable on the work table against the front side of the base-piece to hold the base-piece 100 and attached machine in located position.

ALFRED G. F. KUROWSKI.
